Tobias Cook of Scituate Massachusetts

Letters Patent.

The schedule referred to in these Letters Patent and making part of the same, containing a description in the words of the said Tobias Cook, himself of his improvement in the machinery or apparatus for raising vessels when in the water, without unloading.

To all Persons to whom these presents shall come

I Tobias Cook of Scituate in the county of Plymouth and State of Massachusetts Master Mariner have invented new and useful machinery and apparatus, for raising vessels of all sizes when in the water, without unloading them - and the following specifications are an exact description of the same. a. represents the vessel to be raised. b. represents the lighter by which the vessel a. is to be raised; c. represents the water wheel by which the vessels are propelled, especially in a calm, or with adverse winds. d. represents outboard or driver wheels and sprockets, which carry the beam, upon which rest the ^{crossed} cranes marked h. e. represents the board or driver wheel. f. represents the jack or notched wheel upon the shaft of the driver below, and which carries the driver wheel, & sprockets thereby raising the beam. g. represents the drum below, and connected with the board wheel. h. represents a chain band from the driver wheel. i. represents the tree wheels upon which the horse, or horses travel. l. represents chain bands which pass around and form the drums. m. is the driver shaft. e. f. represents the beam, through which the sprocket (d), passes, and upon which rest the cranes marked h. n. represents the cranes which rest upon the beam marked f. and to which the upper ends of the chains all, are confined, and

To which also said chains are fastened at the middle, and lower end
 L, representing two heavy weights, which pull upon the cranes H, across and above
 the dock of the vessel A, to prevent the lighter B, from crowding
 against the vessel to be raised; M, representing two chains which
 pass under the keel of the vessel A, and is confined to the cranes H,
 and by which the vessel A, is to be raised; N, represent a rest
 or lever ^{or timber} ~~affixed~~ with the cranes H, upon which rest the beam
 marked E; O, represent a gallery by which the cranes H are raised
 P, represents tables by which the cranes H are raised by being con-
 fined to the gallery, Q, represent a stout wooden brace, from
 in the side of which are grooves, where the ends of the bows f, pass
 to keep them steady; R, represent a notched wheel, upon the
 shaft of the water wheel, S, which is carried by segments placed
 underneath the tank-shells; T, represents two soft chains upon the
 heads of the shafts of Pumps G; U, represent two chains fastened
 to the bows of the lighter B, to prevent their spreading.

It will be seen by the within specification that the purchase is
 by the screw E, passing on beam J, thereby raising cranes H, to
 which are fastened the chains marked M, and which chains
 pass under the vessel A.

Having now described the nature of my invention, and
 the manner in which the same is to be performed and carried into
 effect, I would have it understood, that I do not claim to any
 of the various parts taken separately, — But I do claim as my
 invention the combining of the various parts in the manner above
 described in. For witness whereof I have hereunto set my hand
 (Witness) *B. Raymond* *B. K. Russell* *Tabbs Cork.*
